UNITED STATES PATENT OFFICE

153,056

DESIGN FOR AN ELECTRIC LAMP

Martin M. Baker, Port Chester, N. Y.

Application April 15, 1947, Serial No. 138,423

Term of patent 3½ years

(Cl. D48—20)

To all whom it may concern:

Be it known that I, Martin M. Baker, a citizen of the United States, residing at 25 Hillcrest Avenue, Port Chester, New York, in the county of Westchester and State of New York, have invented a new, original, and ornamental Design for an Electric Lamp, of which the following is a specification, reference being had to the accompanying drawing, constituting a part thereof.

Fig. 1 is a front view of an electric lamp, showing my new design.

Fig. 2 is a side view.

Fig. 3 is a fragmentary side view of the opposite side from that shown in Fig. 2.

Fig. 4 is a fragmentary front view showing small hat.

Fig. 5 is a bottom plan view of the base.

The characteristic features of my design reside in the portions shown in full lines.

I claim:

The ornamental design for an electric lamp, substantially as shown and described.

MARTIN M. BAKER.
